CARTRIDGE ACTUATOR FOR A WRITING INSTRUMENT

Emil Hechtle, Mountainside, N.J., assignor to Radianit Pen Corp., Kenilworth, N.J.

Filed Dec. 19, 1966, Ser. No. 5,115

Term of patent 14 years

(Cl. D74—17)

Fig. 1

Fig. 3

Fig. 2

FIG. 1 is a side elevation of the cartridge actuator for a writing instrument showing my new design.

FIG. 2 is a top plan view of the same.

FIG. 3 is a side elevation of the cartridge actuator mounted to the barrel of a writing instrument shown in dash lines, for the purposes of illustration.

A cartridge actuator for detachable positioning at the top of a writing instrument, having as its dominant feature a tapering diamond sided upper bushing supported on a ring-like base with a push-button projecting through the apex thereof, and terminating in an elongated sleeve for threaded insertion into a pen barrel having matching threads.

I claim:

The ornamental design for a cartridge actuator for a writing instrument, as shown and described.
